UNITED STATES PATENT OFFICE.

ARTHUR E. SMALL, OF OAK PARK, ILLINOIS, ASSIGNOR TO UNION METAL PRODUCTS COMPANY, OF CHICAGO, ILLINOIS, A CORPORATION OF DELAWARE.

DEVICE FOR OPERATING CAR COUPLERS.

Application filed October 8, 1924. Serial No. 742,395.

This particular invention relates to what is generally known in the art as a rotating type of uncoupling device for car couplers and comprises an operating rod revolvably 5 mounted on the car with brackets or in any other convenient manner, which rod is usually bent downwardly at the outer end to form a handle, and is bent outwardly at its inner end to form a crank projecting over 10 the coupler lock lifter. The standard vertical plane coupler has a knuckle pivoted to the coupler head and provided with a tail behind which the lock is placed. The lock lifter protrudes through and above the 15 coupler head and is provided with a horizontally positioned eye. This lock lifter eye is $1\frac{1}{16}$ " in diameter and its axis is perpendicular to the longitudinal center of the car. This size and position has been determined by the American Railroad Association 20 and is standard for the majority of couplers now in service.

My invention resides in the connection between the crank of the operating rod and 25 the eye on the coupler lock lifter. When the handle is raised the rod is revolved and the crank is thereby raised which unlocks the coupler by raising the lock lifter.

The coupler moves backwardly and forwardly longitudinally of the car in buffering and draft and also moves sidewise in rounding curves, etc., and the connection between the coupler and the operating rod must permit such movements without the component 35 parts becoming disengaged from each other or from either the coupler or the operating rod. It is frequently necessary to uncouple cars when they are coupled together and in contact so that it is impossible to throw the 40 knuckle of either coupler. To meet this condition couplers are designed to assume a "lock set position" wherein the lock lifter can be raised from behind the tail of the knuckle and retained in such a position by 45 means within the head of the coupler independent of the operating rod. This allows the operating rod to fall close to the lock lifter. To accommodate such a movement the connection between the operating rod 50 crank and the coupler must fore-shorten or have a sliding engagement with either the operating rod or the coupler.

Another object is to provide a connection 55 which may be hooked into the eye of the coupler lock lifter with the hooked member

connected to the crank of the operating rod by another member which permits it to adapt itself to the various service movements of the coupler but prevents it from becoming disengaged from the lock lifter in 60 service.

In the drawings:

Fig. 1 shows a portion of a railway car with my invention applied thereon.

Figs. 2 and 3 show a form of my device 65 with a non-rotative connection to the operating rod.

In a railway car the coupler operating rod 1 is mounted on the end sill 2 by brackets 3 and has a handle 4 at its outer end and a 70 crank arm 5 extending over the coupler. The lock lifter 7 of the coupler 8 has a horizontally disposed eye 9. My invention resides in a connector for the crank arm to the lock lifter. 75

The connector comprises a hook member which is inserted through the eye of the lock lifter and a bar member is then threaded into it so as to close the open portion of the hook. The bar member is then non-rotatively attached to the operating rod so as to prevent it from unscrewing. The operating rod is then mounted upon the car. In certain forms the non-rotative feature is independent of the operating rod. 85

In the form shown in Figs. 2 and 3 the bar 10 is threaded or screwed into the tapped arm 11 of the hook 12 and projects therethrough far enough to substantially close the open portion 13 of the hook so that 90 it cannot become disengaged from the lock lifter 7. A shoulder 14 is provided on the bar 10 which restricts its longitudinal movement and prevents it from binding or interfering with the free relative movement 95 of the hook 12 and the lock lifter 7 (at 15). The longitudinal movement of the bar 10 may be restricted by omitting the shoulder 14 and stopping the threads at such a point 100 on the bar 10 that it cannot be threaded into the hook 12 further than a predetermined amount. In Fig. 2, for instance, the top of the threads in bar 10 would reach the top of the hook 12 at the same time the bottom end of the bar is close to the lock lifter 7, 105 all as shown. The bar has a non-rotative attachment with the operating rod 1 which prevents it from unscrewing or backing out of the hook 12, but this attachment also preferably provides a relative sliding arrange- 110

ment between the operating rod and the bar. Any non-rotative attachments between the bar and the operating rod may be used and come within the scope of this invention.

5. The hook is circular (with one portion open) having a center at 16 which is in line with the longitudinal axis of the bar so that there is no eccentric load on the device.

I claim:

10. 1. In a device for operating a car coupler, the combination of a coupler lock lifter having an eye, a hook engaging said eye, a bar closing the open portion of the hook and having a threaded engagement with the hook; and means to prevent the rotation of the bar whereby said bar and said hook are retained in proper relative position.

20. 2. In a device for operating a car coupler, the combination of a coupler lock lifter having an eye, a hook engaging said eye, a bar closing the open portion of the hook and having a threaded engagement with the hook and provided with a shoulder to restrict its longitudinal movement, and means

25. to prevent the rotation of the bar whereby said bar and said hook are retained in proper relative position.

30. 3. In a device for operating a car coupler, the combination of a coupler lock lifter having an eye, a circular hook engaging said eye, and a bar closing the open portion of said hook and having a threaded engagement therewith, the center of said circular hook being in line with the longitudinal axis

35. of said bar.

40. 4. In combination with a railway car provided with a coupler and a coupler operating rod, a connector for said coupler and operating rod comprising a member non-rotatively engaged to said coupler, and another member non-rotatively engaged to said operating rod, one of said members being threaded into the other whereby said members are retained in proper relative relation.

45. 5. A connector for a railway car coupler, and its operating rod comprising an open hook, and a bar closing the open portion of the hook and having a threaded engagement therewith, and means to prevent the rotation of the bar.

50. 6. A connector for a railway car coupler, and its operating rod comprising an open hook, a bar closing the open portion of the

hook and having a threaded engagement therewith and provided with a shoulder to restrict its longitudinal movement, and means to prevent the rotation of the bar.

55. 7. In a release rigging for a car coupler, the combination of an operating rod, a coupler lock lifter having an eye, a hook engaging said eye, and a bar closing the open portion of said hook and having a threaded engagement with said hook, said bar having a non-rotative engagement with said operating rod whereby said bar and said hook are retained in proper relative relation.

60. 8. In a release rigging for a car coupler, the combination of an operating rod, a coupler lock lifter having an eye, a hook engaging said eye, and a bar closing the open portion of said hook and having a threaded engagement with said hook and provided with a shoulder to restrict its longitudinal movement, said bar having a non-rotative engagement with said operating rod whereby said bar and said hook are retained in proper relative relation.

65. 9. In a release rigging for a car coupler, the combination of an operating rod, a coupler lock lifter having an eye, an open hook engaging said eye, a bar closing the open portion of said hook and having a threaded engagement therewith, and means to prevent the rotation of the bar, said bar operatively connected to the operating rod.

70. 10. In a release rigging for a car coupler, the combination of an operating rod, a coupler lock lifter having an eye, an open hook engaging said eye, a bar closing the open portion of said hook and having a threaded engagement therewith, said bar provided with a shoulder to restrict its longitudinal movement, and means to prevent the rotation of the bar, said bar operatively connected to the operating rod.

75. 11. A connector for a railway car coupler and its operating rod, comprising an open hook, and a bar closing the open portion of the hook and having a threaded engagement therewith.

80. 12. A connector for a railway car coupler and its operating rod, comprising an open hook, and a bar closing the open portion of the hook and having a threaded engagement therewith and provided with a shoulder to restrict its longitudinal movement.
